UNITED STATES PATENT OFFICE.

SAMUEL J. McDONALD, OF GALLATIN, MISSOURI.

WIRE-STRETCHER.

SPECIFICATION forming part of Letters Patent No. 323,054, dated July 28, 1885.

Application filed August 26, 1884. (No model.)

To all whom it may concern:

Be it known that I, SAMUEL J. McDONALD, a citizen of the United States, residing at Gallatin, in the county of Daviess and State of Missouri, have invented certain new and useful Improvements in Wire-Stretchers, of which the following is a specification, reference being had therein to the accompanying drawings.

10 My invention relates to devices for stretching and splicing wire used for wire-fences.

The invention consists in certain details of construction and arrangement of the several parts, as will be hereinafter more fully set forth in the specification, and pointed out in the accompanying drawings, in which—

Figure 1 is a side elevation of my device, showing the device as used for stretching wire, and Fig. 2 a similar view in which the device 20 is shown as used for splicing wire.

The device consists of a frame having a top notched bar, A, and under guide-bar, A'. At one end is a hook, G, the opposite end having a clamp, F', actuated by pivoted bars F, pivoted 25 at f, and acting on the principle of the lazy-tongs. This clamp holds one end of the wire to be spliced or tightened. Between the bars A A' is a guide-rod, B B', actuated by a lever, D, secured thereto, and the pawl-clamps 30 E C, pivotally secured to the lever and rod, as shown in both the figures. At the outer end of the rod B is a cutter consisting of the bars H H', pivoted to each other, the outer end of the bars H having shears or cutting portions H² and a gripping end, h. When used for stretching wire, a chain, K, is secured to a post, P, and one of its links is secured to a hook, I, which hooks into the hook on bar or rod B, leaving several links hanging loose. The

front gripper is then closed on the wire, and 40 the stretcher is shortened up by the lever D, if the wire is still too loose, the loose end of the chain is fastened to the hook end G of the slotted bar A A', and the rod run back and the rear hook fastened in a link farther back 45 on the chain, and the stretcher again shortened up, and so on until the wire is sufficiently tight. In this operation the rear gripper is not used, of course, but hangs loose. In splicing wire the two ends of the broken wire are 50 caught in the gripper, one in each—say a foot along the wire. The stretcher is then shortened by the lever motion until the two ends of the broken wire meet, when they can be spliced in any well-known or desired manner, such 55 as lapping the ends or using extra splicing-wire. The device is easily and quickly used, is light and portable, and does not easily get out of order.

Having described my invention, what I 60 claim is—

In a wire-stretching device, the combination, with the slotted bar having serrations on one side, of the pivoted bars and clamp pivotally secured at one end of said bar A, and a hook, 65 G, at the opposite end, the lever D and its pawl, the sliding rod B and its pivoted pawl, and the pivoted bars H H', bars H being provided with gripping and cutting ends, as described, and bars H' being secured to the outer 70 end of the sliding rod, substantially as and for the purpose set forth.

In testimony whereof I affix my signature in presence of two witnesses.

SAMUEL J. McDONALD.
